UNITED STATES PATENT OFFICE.

PHILIP B. HARRISON, OF CHICAGO, ILLINOIS, ASSIGNOR TO THE CHICAGO RAILWAY EQUIPMENT COMPANY, OF SAME PLACE.

BRAKE-BEAM.

SPECIFICATION forming part of Letters Patent No. 621,079, dated March 14, 1899.

Application filed December 30, 1897. Serial No. 664,574. (No model.)

To all whom it may concern:

Be it known that I, PHILIP B. HARRISON, a citizen of the United States, residing at Chicago, in the county of Cook, State of Illinois, have invented certain new and useful Improvements in Brake-Beams; and I hereby declare the following to be a full, clear, and exact description of the same, reference being had to the accompanying drawings, in which—

- 10 Figure 1 is a plan view of a brake-beam, one end broken away to show a construction which embodies my invention. Fig. 2 is an enlarged end view of the brake-beam, the brake-head being in section on the line xx , Fig. 3, to show an end view of the devices embodying my invention. In Fig. 2 the brake-beam is shown as improperly hung—that is to say, with the tension member and strut inclined to the plane of the track. Fig. 15 20 25 30 35 40 45 50 55 60 65 70 75 80 85 90 95 100
- Fig. 3 is an enlarged view of the end of the brake-beam, also broken away, as in Fig. 1, to show the construction which embodies my invention. Fig. 4 is a detached perspective view, still further enlarged, of the end of the compression member and the slip-sleeve embodying my invention. Fig. 5 is a transverse sectional view of the compression member and sleeve, taken on the line yy , Fig. 4. Fig. 6 is a transverse sectional view of the compression member and sleeve, taken at the same point as Fig. 5, showing a modification in which the slot in the slip-sleeve is no wider than will permit the passage of the tension member.
- 35 Like symbols refer to like parts wherever they occur.

My invention relates to the construction of that class of trussed metallic brake-beams wherein are combined a tubular compression member, a strut or post, a tension member, and a brake-head, and has for its objects, first, to transfer the torsional strain (heretofore exerted by the brake-head on the compression member) to the tension member, and thus to relieve the compression member of torsional strain when the beam is improperly hung, and, second, to increase the end bearing of the brake-head and proportionately reduce the slack incident to the wear between the parts necessarily arising in service. In brake-beams of this class where the compression

member is hollow, whether the same be a complete tube slotted or indented for the passage of the tension-rod or an incomplete tube having a longitudinal slot through which the tension-rod passes, the end bearing between the brake-heads and the compression member is necessarily limited to that afforded by the thickness of the metal in the tube, and this under the constantly-recurring movement or spring of the compression member in the heads tends to wear away the bearing and produce slack in the beam, which is highly objectionable. Furthermore, as in this class of brake-beams the head is fixed in a given position on the compression member and bears a definite position with relation to the tension-rod and strut, if the beam is improperly hung—that is to say, the strut and tension-rod are canted out of a horizontal plane—when the brakes are applied the strain will always tend to draw the strut and tension-rod into a horizontal position, which, being resisted by the brake-heads, (which bear on the wheels,) will result in the transfer of the load from the tension member to the compression member, and a torsional strain will be exerted on the compression member at its weakest points. To overcome these several objectionable features of construction, I combine with the tension member, compression member, and brake-head a slip-sleeve confined as to longitudinal movement on the compression member and provided with means for engaging the brake-head and fixing the "throw" thereof, whereby either by the rotary movement of the slip-sleeve on the compression member or the rotation of the compression member, as the case may be, all torsion passes from the brake-head directly to the tension member to the relief of the compression member, and such a construction embodies the main feature of my invention.

There are other minor features of invention, all as will hereinafter more fully appear.

I will now proceed to describe my invention more fully, so that others skilled in the art to which it appertains may apply the same.

In the drawings, A indicates the compression member, B the post or strut, C the tension member or truss-rod, D D the brake-

heads, and *c c* the tension-nuts of a trussed brake-beam, which may be such as herein shown or any of the approved forms of beams, provided the back or compression member is substantially tubular and has end bearings in the brake-heads or their equivalents.

In the present instance the compression member A is shown as a complete tube or pipe slotted, as at *a*, for the passage of the 10 end of the tension member C, the tongue of metal *a'* being left attached, though the same may be removed, if desired. The end of the compression member is notched, as at 1, and in prior constructions of the beam this notch 15 has been of a width substantially the width of lug or projection *d* on the interior of brake-head D, (see Fig. 3,) which lug it received, so as to prevent the rotation of the brake-head and by its location determine the throw 20 of the brake-head in "underhung" beams. In my present construction this notch 1 in the end of the compression member has a different purpose and does not receive the lug *d*. It is therefore made much wider than said lug 25 and receives a narrow tongue or lug on the slip-sleeve E to prevent the longitudinal movement of slip-sleeve E on the compression member A, but permit of a limited rotary movement between the sleeve E and compression 30 member A.

E indicates a slip-sleeve, which may be a short section of pipe or a cylindrical malleable casting of such length as to extend from the end of the compression member A to a 35 point within which the tension member C enters the compression member A, the inner diameter of said slip-sleeve being slightly greater than the exterior diameter of the compression member. Slip-sleeve E is slotted, 40 as at 3, for the passage of the tension member C, and said slot may be no wider than will permit the passage of the tension-rod C; but is preferably of such width as will allow 45 of a slight rotary movement of the slip-sleeve on the compression member.

In the outer end of the slip-sleeve E, at a point corresponding with notch 1 of the compression member, is a notch 4 to receive the lug *d* on the interior of brake-head D, (see 50 Fig. 3,) and said notch, which is only of sufficient width to receive the lug *d* and prevent the rotation of the brake-head, thus fixing the throw of the head, is preferably formed by depressing a tongue 5, which enters the 55 notch 1 in the end of the compression member A and prevents the longitudinal movement of the slip-sleeve E on the compression member, while (owing to the width of notch 1) it permits a slight rotary movement of said 60 sleeve.

It is evident that other means may be employed to prevent the longitudinal movement of the slip-sleeve E on the compression member A and retain the ends of sleeve and compression member in the same plane—as, for 65 instance, a collar on the compression member, (see full lines, Fig. 1;) but I prefer the

tongue 5 as the simplest and least expensive means.

The construction of the parts being substantially such as hereinbefore pointed out, 70 they are assembled by first placing the strut or post B in position on the compression member A and then applying the slip-sleeves E to the end of the compression member with 75 the tongues 5 in the notches 1 in the ends of the beam, after which the brake-heads D are slipped on the sleeves E, with the lugs *d* entering the notches 4 in the ends of the sleeves E, and finally the ends of the tension-rod C are passed through the slip-sleeves, 80 compression member, and brake-heads, and the whole secured by the tension-nuts *c c*, the latter being tightened to take all slack from the structure and to camber the compression member, if desired.

When in service, the increased end bearing between the compression member and the brake-heads due to the double thickness of metal will materially reduce wear and lost 90 motion, and at the same time if the beam be improperly hung, the strut and tension member canted, (see Fig. 2,) the torsional strain, (when the brakes are applied,) which would otherwise be transferred from the tension 95 member through the compression member to the brake-heads, will, owing to the limited rotary movement between the compression member and slip-sleeve, pass from the tension member through the slip-sleeves to the 100 brake-heads, thus relieving the compression member, which will be subjected to compressive strains only.

Having thus described my invention, what I claim, and desire to secure by Letters Patent, is—

1. In a brake-beam, having a strut, a tension member, a compression member and a brake-head, the combination with the compression member of a loose or slip sleeve capable of rotary movement on the compression member and provided with a slot for the entrance of the tension member and means for engaging the brake-head; substantially as and for the purposes specified.

2. In a brake-beam, having a strut, a tension member, a compression member, and a brake-head, the combination with the compression member of a loose or slip sleeve capable of rotary movement on the compression member, and provided with a slot for the entrance of the tension member and a notch for engaging a lug in the brake-head; substantially as and for the purposes specified.

3. In a brake-beam having a strut, a tension member, a compression member and a brake-head, the combination with the compression member of a loose or slip sleeve capable of rotary movement on the compression member and provided with means for engaging the tension member and the brake-head; substantially as and for the purposes specified.

4. In a trussed brake-beam, the combina-

tion with a compression member having an end notch, of a slip-sleeve having a tongue which engages in the end notch of the compression member and a notch to receive a lug in the brake-head, a brake-head having a lug which engages in the notch of the slip-sleeve, and a tension member, substantially as and for the purposes specified.

In testimony whereof I affix my signature, in presence of two witnesses, this 28th day of 10 December, 1897.

PHILIP B. HARRISON.
